SHAFT FOR GOLF CLUBS AND THE LIKE

Harold G. Barrett, Wilmette, Ill., assignor, by
mesne assignments, to General Automatic
Corp., Chicago, Ill., a corporation of Illinois

Application June 14, 1929, Serial No. 370,791

2 Claims. (Cl. 273—80)

This invention relates in general to golf clubs, but more specifically to the shaft employed in connection therewith.

Heretofore with iron head golf clubs the shafts have been constructed of wood and as they are subjected to moisture and changing temperature, the shafts not only absorb the moisture but they frequently warp and split. Metal shafts if used, will corrode and rust, causing the paint to peel or 10 chip off, resulting in an unsightly appearance.

Heretofore in applying metal shafts to iron heads it has been necessary to employ what is commonly known as an "adaptor" for adapting such shafts for use with an iron head. It has 15 also been attempted to shape metal shafts to be secured to iron heads to give the shaft the appearance of a wooden shaft by what might be termed "building up" the shaft by sleeving a flared ferrule thereover and securing the same to the shaft 20 at the desired point, after which a casing has been sleeved over the shaft and ferrule, but in order to accomplish this it is necessary to stretch the casing to provide a flare at one end to receive and accommodate the ferrule.

It is one of the objects of the present invention to overcome these objections and difficulties and to provide for the shafts of iron head clubs a casing or covering having tensile strength, which will not only reinforce the shaft to which it is applied, 25 but will possess the necessary flexibility so as not to impair the flexibility of the shaft, and at the same time cause the finished product to have the appearance of a standard wood shafted iron, whether a wood shaft is actually employed or 30 whether a metallic shaft is employed, and if a metallic or steel shaft is employed, the club will 35 possess all of the attributes of both a wooden and a metallic shaft.

It is another object of the present invention to 40 dispense with the use of an adaptor by shaping or building up the casing itself either exteriorly or interiorly so as to provide the flare usually formed at the end of the wooden shaft which is inserted into the socket of the head, thereby dispensing with the necessity of stretching or shaping 45 the body portion of the casing to form a flared portion to receive such adaptor.

To the attainment of these ends and the accomplishment of other new and useful objects 50 as will appear, the invention consists in the features of novelty in substantially the construction, combination and arrangement of the several parts hereinafter more fully described and claimed and shown in the accompanying drawing illustrating 55 this invention, and in which

Figure 1 is a side elevation of an iron head golf club constructed in accordance with the principles of this invention.

Figure 2 is a longitudinal sectional view of a portion of a shaft and a casing therefor showing one step in the method of producing or manufacturing the shaft. 5

Figure 3 is a view similar to Figure 2, showing the finished product.

Figure 4 is an enlarged detail sectional view of 10 one end of the finished casing or covering.

Figure 5 is a view of a modified form of the invention.

Figure 6 is a view of another modified form of 15 the invention.

In carrying this invention into practice the casing is shown as applied to a tubular metallic shaft, but it is to be understood that the same may be applied to a shaft which is solid or which 20 may be of wood or metal suitably shaped.

The casing 10 is constructed of any suitable non-metallic, hard, flexible material such as pyroxyline which is preferably such that it is adapted to be made soft and pliable when subjected to a predetermined degree of heat, thereby adapting 25 the same to be placed upon or sleeved over the shaft to be fashioned to conform to the contour of the shaft, the properties of the material being such that as the casing becomes cool, it will shrink about the core upon which it is placed, or the casing may be allowed to become cool before applying to the shaft or core so that the two may be 30 secured together by a wedging action.

As shown in the drawing the shaft 11 is usually 35 provided with a reduced and tapered extremity 12 that is adapted to be inserted into the socket end 13 of an iron head 14. The periphery of the casing 10 adjacent one end thereof may be reduced as at 15, to provide a circumferential shoulder 16, and telescoped upon such reduced end is a 40 sleeve 17 preferably constructed of the same material as the material from which the casing 10 is formed. One end of the sleeve 17 abuts the circumferential shoulder 16 and the other end of the sleeve 17 preferably terminates flush with the adjacent end of the sleeve or casing 10. The internal diameter of the sleeve 17 is such that it 45 will fit tightly upon the reduced portion 15 of the sleeve or casing 10 and may be secured against displacement with respect thereto in any desired 50 or suitable manner, such as by means of glue, cement, or other fastening means.

The casing embodying the sleeves 10 and 17 when thus assembled may be telescoped upon 55 the shaft 11 so as to fit tightly thereupon, the

sleeve or casing 10 being so placed upon the shaft that the extremity 12 of the shaft 11 will project beyond one end thereof as shown in Figure 2.

The casing embodying the sleeves 10 and 17 is then finished in any suitable manner, or may be finished before being placed upon the shaft, either by a grinding or cutting operation upon the periphery thereof to produce in the sleeve 17, a taper from the extremity 18 toward the other end thereof and the taper is such that the portion of the sleeve 17 adjacent the circumferential shoulder 16 will be flush with or merge into the periphery of the sleeve or casing 10, so as not to form a shoulder or a sharp edge at the end of the sleeve, and the joint will not be visible. At the same time the periphery of the end 18 of the sleeve 17 will be flared.

With this construction and when the end 12 of the shaft 11 is inserted in the socket 13 of the head 14, the end 18 of the sleeve 17 and the adjacent end of the sleeve or casing 10 will abut the edge of the socket 13, with the result that when the parts are assembled the shaft will have the appearance of a flared wooden shaft.

Obviously the sleeve 17 and the casing 10 may be of the same or of different colors, thereby enhancing the beauty or appearance of the finished product.

In the form of the invention shown in Figure 5, the same results are produced, but the effect and result accomplished by the combination of the sleeve 17 and shaft or casing 10 will be produced in an integral structure. In this form of the invention the sleeve or casing 20 will be formed of a uniform or substantially uniform thickness throughout its length, and may then be fashioned by grinding or cutting away the periphery thereof to produce a flared extremity 21, tapering as at 22 from the extremity 23 toward the opposite end thereof. The pitch of the taper may be of any degree and when so constructed, the finished sleeve or casing may be applied to the shaft 11 in the same manner as with the other forms of the invention, or if desired the casing 20 may be applied to the shaft before the periphery thereof is finally shaped.

In the form of the invention shown in Figure 6 the same results are produced, but the sleeve or casing having the flared end is of an integral construction.

In this form the sleeve or casing 10^a may be slightly tapered and the end 10^b is of a greater thickness, the outer surface 10^c of the end 10^b tapering from the extremity of the casing 10 towards the opposite end thereof and in a direction opposite to the direction of the internal taper of the sleeve 10^a.

Obviously, in all forms of the invention the tube or casing may if desired be of a substantially uniform internal diameter throughout its length.

It will therefore be manifest that when a casing of this character is employed it will not only protect the wooden shaft from the action of the elements and from warping, but will have the desired flexibility so as not to impair the flexibility of the shaft. At the same time by the use of this invention, low grade wood may be employed for the shaft.

Furthermore with the present invention it is possible to produce a thick portion at the bottom of the sheath without any waste of material, and yet employ thin tubing, as the sleeve 17 is telescoped over the reduced end of the casing 10 and then milled down. At the same time with the present invention the sleeve 17 may be of any color desired contrasting with the color of the sheath, and no shoulder will be formed at the junction of the sleeve and the shoulder on the 10 casing.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. In a golf club, the combination with a metal head provided with a hosel having a socket therein, the end of the socket being of substantial extent radially and disposed at substantially right angles to the longitudinal axis of the socket, a metal shaft fitting and fixedly secured within said socket metal to metal, a relatively thin casing of hard, flexible, non-metallic material secured around the periphery of the shaft to form an end spaced a substantial distance from the lower end of the shaft, said end being of substantial extent radially and abutting the socket end, the outer periphery of said casing being cut away from said end for a considerable extent in a direction lengthwise of the shaft to form a circumferential shoulder spaced from the end of the casing, and a sleeve arranged and fixedly secured on said casing, one end of the sleeve abutting said shoulder and the other end being substantially flush with the end of the casing and forming therewith an end of substantial area abutting the end of the socket.

2. In a golf club, the combination with a metal head provided with a hosel having a socket therein, the end of the socket being of substantial extent radially and disposed at substantially right angles to the longitudinal axis of the socket, a metal shaft fitting and fixedly secured within said socket metal to metal, a relatively thin casing of hard, flexible, non-metallic material secured around the periphery of the shaft to form an end spaced a substantial distance from the lower end of the shaft, said end being of substantial extent radially and abutting the socket end, the outer periphery of said casing being cut away from said end for a considerable extent in a direction lengthwise of the shaft to form a circumferential shoulder spaced from the end of the casing, and a sleeve arranged and fixedly secured on said casing, one end of the sleeve abutting said shoulder and the other end being substantially flush with the end of the casing and forming therewith an end of substantial area abutting the end of the socket.

3. In a golf club, the combination with a metal head provided with a hosel having a socket therein, the end of the socket being of substantial extent radially and disposed at substantially right angles to the longitudinal axis of the socket, a metal shaft fitting and fixedly secured within said socket metal to metal, a relatively thin casing of hard, flexible, non-metallic material secured around the periphery of the shaft to form an end spaced a substantial distance from the lower end of the shaft, said end being of substantial extent radially and abutting the socket end, the outer periphery of said casing being cut away from said end for a considerable extent in a direction lengthwise of the shaft to form a circumferential shoulder spaced from the end of the casing, and a sleeve arranged and fixedly secured on said casing, one end of the sleeve abutting said shoulder and the other end being substantially flush with the end of the casing and forming therewith an end of substantial area abutting the end of the socket, the peripheries of the sleeve being respectively flush with the periphery of the hosel end and the periphery of the casing at the point of abutment with the said shoulder.

HAROLD G. BARRETT.
